ELECTRIC SWITCH OF THE FLUID FLOW
TYPEWarren R. Walker, Short Hills, N. J., assignor to
General Electric Vapor Lamp Company, Ho-
boken, N. J., a corporation of New Jersey

Application October 29, 1935, Serial No. 47,299

6 Claims. Cl. (200—152)

The present invention relates to electric switches of the fluid flow type, and particularly to switches employing mercury to close the circuit therethrough.

5 A particular object of the invention is to provide a fluid flow switch having an extremely low resistance. A further object of the invention is to provide a fluid flow switch which will have a long useful life. Still other objects and advantages of my invention will appear from the following detailed specification or from an inspection of the accompanying drawing.

The invention consists in the new and novel structure hereinafter set forth and claimed.

15 In general the current rupturing capacity of a fluid flow switch considerably exceeds the current which the same switch can continuously carry with an approved temperature rise, and the rating of the switch is therefore necessarily limited to the smaller value imposed by the latter of these considerations. This limiting temperature rise within the switch is, of course, a direct function of the internal resistance of the switch, and hence any decrease in this resistance is immediately reflected in an increased rating for 20 the switch. Accordingly a great deal of effort has been expended in an attempt to reduce the internal resistance of these switches.

Recently considerable attention has been directed toward the development of switches having a metal envelope, in which different portions of this envelope serve as the electrodes. This construction has provided electrodes having a very considerable area in contact with the mercury 25 commonly used as the fluid in these switches, and has thus tended to produce a switch having a low internal resistance. This general idea of a metal envelope switch has, of course, been toyed with for many years, but it is only since the recent 30 development of switches of this type having vitreous seals, such as disclosed in an application by John H. Payne, Jr., Ser. No. 759,927, filed December 28, 1934, whereby they are hermetically sealed for the first time, that a successful commercial 35 structure has been attained. The production of these vitreous seals, however, requires the use of a fusing heat and this heat, while essential to the production of a successful switch, tends to produce an oxide film on the surface of any of the 40 metals which it is practicable to use for these envelopes. The presence of this film is indicated by the fact that the resistance of these switches, while very low, is sometimes above that which would be obtained with a clean metal surface 45 50 55 which would be wet by the mercury. Further-

more I have found that many of the metal alloys which are commonly used in combination with soft glass, such as the various chrome-iron alloys which it is known can be sealed to the soft glasses, are not wet by mercury even when perfectly clean.

I have now discovered that the resistance of any of these switches is maintained at a constant low value by providing the inside of the metal shells forming the switch with a surface consisting of platinum, which I have found to be unique in possessing two essential characteristics for this contact surface. Thus first of all the platinum does not oxidize during the heating operations which are necessary to fuse together the 15 various elements of the switch, so that a clean metal surface is presented to the mercury. Even more important this clean platinum surface is readily wet by the mercury to produce an exceptionally good electrical contact therewith, but is 20 not dissolved away to any appreciable extent by the mercury, due to its low solubility therein, so that an extremely thin film can be depended upon throughout the long life of the switch. It is not 25 essential, or even desirable, that the platinum cover the entire inner surface of the metal shells, since I have found that a very small area thereof located on each shell where it will make contact with the mercury when the circuit through the switch is closed is entirely adequate to give 30 an extremely low resistance, and that by locating these areas somewhat toward the open circuit position of the switch the angle of tilt required to open and close the circuit is diminished.

The desired platinum surface is produced in 35 any of a variety of ways. Thus in the preferred case a small piece of sheet iron coated with a thin film of platinum on the exposed side is welded in place in the metal shells. Or a fine wire sheathed in platinum, of the order of 10 mils in 40 diameter, is welded end on to the metal shell and clipped off as short as possible. In either of these cases, of course, pure platinum can also be used, but the use of an iron base for the platinum 45 coatings permits the use of larger pieces at the same small cost, and thus not only simplifies the handling problem, but also exposes a larger surface to the mercury for a given quantity of platinum than would otherwise be convenient. Likewise the platinum may be coated on other base 50 metals which will not contaminate the mercury, if desired, although iron has been found to be especially valuable for this use. As an alternative to this welding the coating of the platinum is produced by depositing the metal out of a sus- 55

pension or solution of a salt thereof by any of the well known methods, or it can be plated on the shell.

In any of the above cases a small contact surface of platinum is formed at a point which is below the mercury in the closed circuit position of the switch which is not only free of oxide, but which is slightly wetted by the mercury, although it does not dissolve therein to any appreciable extent. This wetting of the contact surface results in an unusually constant and good electrical conduction from the platinum to the mercury, and as a result the internal resistance of the switches constructed in this novel manner is exceptionally low.

For the purpose of illustrating my invention I have shown a preferred embodiment thereof in the accompanying drawing, in which

Fig. 1 is an elevational view of a mercury switch having a hermetically sealed metal envelope,

Fig. 2 is a sectional view of the switch of Fig. 1,

Fig. 3 is an internal view of one of the metal sides of the switch of Fig. 1 before assembly showing a piece of platinum or platinum coated iron welded thereto,

Fig. 4 is an elevational view of the refractory dividing member shown in the position in which 30 it is placed in the metal part shown in Fig. 3.

Fig. 5 is an enlarged section of a part of the metal side shown in Fig. 3 showing the preferred mode of attaching the platinum,

Fig. 6 is a similar view to Fig. 5 showing a 35 modification of the structure thereof using wire, and

Fig. 7 is a side view of the switch of Fig. 1 showing the relation of the various parts thereof within the switch by means of dotted lines.

40 As shown in this drawing my novel switch, which is of the type disclosed in my co-pending application, Serial No. 28,560, filed June 26, 1935, has two dished metal members 1 and 2 which are identical, save that the member 1 has a filling opening therein. Between said members 1 and 2 there is positioned a refractory dividing member 3 with a thin coating of glass 4 hermetically sealing the members 1 and 2 to each other and to the member 3. Within said switch 45 there is a body of mercury 5 which is adapted to close the circuit between the members 1 and 2 through an opening 6 in the refractory 3 at one position of the switch. Said switch is preferably filled with hydrogen or other suitable arc 50 suppressing gas at a pressure of the order of an atmosphere or more, and is sealed by means of a closure 7 fused within the previously mentioned filling opening in the member 1.

55 At a point which is below the surface of the mercury 5 whenever said mercury extends through the opening 6, and preferably at a point which is not quite opposite said opening, as best shown in Fig. 7, a piece of sheet metal 8, which consists of platinum or platinum coated iron, is 60 welded to each of the metal members 1 and 2. In practice these metal strips are of the order of 2 by 4 millimeters in size, and are of 10 mil iron on which there has been rolled or otherwise placed a coating of platinum of the order of .2 65 mil in thickness.

70 In the alternative form of Fig. 6 a platinum or platinum sheathed wire 8' of the order of 10 mils in diameter is welded end on to each of the metal shells, and the free end thereof then 75 clipped off fairly close. This gives a desired low

resistance and at the same time economizes on the use of the platinum. In some cases the wire 8' is welded on its side against the members 1 and 2, but in general better results are obtained with the structure shown for a given mass of 5 platinum.

In the manufacture of these switches the platinum contacts 8 or 8' are welded in place, as shown, or an equivalent coating of the metal is deposited thereon from solution or suspension, 10 by plating, or in any other suitable manner, and the switch then assembled and fused together, preferably in the manner described in Payne's application or in my co-pending application, referred to hereinbefore. The contacts 8 or 8' 15 remain unoxidized, of course, despite the heating to which the members 1 and 2 are necessarily subjected during the fusion step, due to the characteristics of the platinum. After the switch has been evacuated it is given its filling of 20 mercury 5 and hydrogen and then sealed-off by fusing the closure 7 in place.

The switch is then heated to a temperature of the order of 150° C. while in such a position that the mercury 5 is in contact with the contacts 25 8 or 8', either by placing it in an oven or by passing a suitable current therethrough. This heating greatly facilitates the wetting of the platinum by the mercury, with a resultant decrease in the contact resistance therebetween. 30

The contacts 8 or 8' are preferably positioned a little out of alignment with the opening 6, as shown, since in this position these contacts remain below the surface of the mercury as the switch is rotated between its open and closed circuit position. This prevents the attraction between the mercury and the wetted platinum from exerting a drag on the mercury on either movement of the switch, and thus results in operation of the switch with a minimum angular movement thereof.

While I have described my invention by reference to a particular embodiment thereof it is to be understood that various changes, omissions and substitutions within the scope of the appended claims, may be made therein without departing from the spirit of my invention.

I claim as my invention:—

1. An electric switch comprising, in combination, a pair of metallic members hermetically sealed together to form a substantially all metal envelope, said members being insulated from each other, mercury within said envelope in contact with said metallic members over an extensive area, said envelope having a relatively high contact resistance with said mercury despite said large contact area, a refractory member dividing said envelope into two chambers, said refractory member having an opening therein to permit mercury flow therethrough in the closed circuit position of said switch to electrically connect said metallic members, and a coating of platinum of relatively small area in electrical contact with each of said metallic members and with said mercury when said switch is in said closed circuit position to reduce the electrical resistance between said members and said mercury.

2. An electric switch comprising, in combination, a pair of metallic members hermetically sealed together to form a substantially all metal envelope, said members being insulated from each other, mercury within said envelope in contact with said metallic members over an extensive area, said envelope having a relatively high contact resistance with said mercury despite said

large contact area, a refractory member dividing said envelope into two chambers, said refractory member having an opening therein to permit mercury flow therethrough in the closed circuit 5 position of said switch to electrically connect said metallic members, and a coating of platinum of relatively small area in electrical contact with each of said metallic members and with said mercury when said switch is in said closed circuit 10 position, said platinum coatings being wetted by said mercury to make good electrical contact therewith to reduce the electrical resistance between said members and said mercury.

3. An electric switch comprising, in combination, a pair of metallic members hermetically sealed together to form a substantially all metal envelope, said members being insulated from each other, mercury within said envelope in contact with said metallic members over an extensive 15 area, said envelope having a relatively high contact resistance with said mercury despite said large contact area, a refractory member dividing said envelope into two chambers, said refractory member having an opening therein to permit 20 mercury flow therethrough in the closed circuit position of said switch to electrically connect said metallic members, and a coating of platinum of relatively small area in electrical contact with each of said metallic members and with said 25 mercury when said switch is in said closed circuit position, said coatings being so positioned in an offset relation with respect to the opening in said refractory member that they are completely below the surface of said mercury in both the open 30 and closed circuit position of said switch to re-

duce the electrical resistance between said members and said mercury.

4. In combination, a body of mercury, a metallic member of oxidizable metal in extensive contact therewith, said member having a relatively 5 high contact resistance with said mercury despite said extensive contact area, and a coating of a non-oxidizable metal on a relatively small portion of said member as compared to the portion thereof in direct contact with said mercury, said 10 coating being in contact with said mercury to reduce the resistance of the electrical path from said member to said mercury.

5. In combination, a body of mercury, a metallic member of oxidizable metal in extensive contact therewith, said member having a relatively 15 high contact resistance with said mercury despite said extensive contact area, and a coating of platinum on a relatively small portion of said member as compared to the portion thereof in 20 direct contact with said mercury, said coating being in contact with said mercury to reduce the resistance of the electrical path from said member to said mercury.

6. A sealed device consisting in part of vitreous 25 material, mercury within said device, a metallic member of oxidizable metal sealed to said vitreous material and in extensive contact with said mercury, and a coating of platinum affixed to a relatively small portion of said member as compared 30 with the portion thereof which is in direct contact with said mercury, said coating being in contact with said mercury to reduce the electrical resistance of the path from said member to said mercury. 35
